CONVERTIBLE WEB PRINTING PRESS

Howard M. Barber, Pawcatuck, Conn., assignor
to C. B. Cottrell & Sons Company, Westerly,
R. I., a corporation of Delaware

Application November 28, 1934, Serial No. 755,148

6 Claims. (Cl. 101—177)

The object of my invention is to provide a convertible web printing press which may, with a minimum amount of change and substitution of parts, be successfully used for either offset or relief printing, in a plurality of colors, upon a traveling web.

My invention comprises a plurality of pairs of change cylinders spaced around a common cylinder, each pair of change cylinders, when used for offset printing, consisting of a design and a transfer cylinder, and when used for relief printing, consisting of a form and an impression cylinder; the common cylinder serving as an impression cylinder when the press is used for offset printing and as a rotary carrier for the web when the press is used for relief printing.

Practical embodiments of my invention are represented in the accompanying drawings, in which

Fig. 1 represents a diagrammatic side view, showing the press adapted for offset printing;

Fig. 2 represents a similar view, showing the press adapted for relief printing; and

Fig. 3 represents a detail side view of the gearing constituting the drive for the press.

The traveling web is denoted by 1 and its web supply and rewinding rolls by 2 and 3 respectively; which rolls are herein shown as being both located at the same end of the press, although this arrangement is not essential to the operation of the press.

The printing press frame is denoted by 4 and in it are rotatably mounted a common cylinder 5 and a plurality of pairs of change cylinders arranged around the common cylinder. In the present instance the pairs of cylinders are shown as one-half the size of the common cylinder and with two pairs of cylinders arranged in upper and lower spaced relationship on each side of the common cylinder.

When the press is used for offset printing, each pair of change cylinders comprises a design cylinder 6 and a transfer cylinder 7; the cylinder 5 in this instance serving as a common impression cylinder for all of the transfer cylinders 7.

When the press is used for relief printing, each pair of change cylinders comprises a form cylinder 6* and its impression cylinder 7*; the common cylinder in this instance serving as a rotary carrier for the web on its way to the several pairs of form and impression cylinders, to insure color registry.

Inking mechanisms 8 of any well known or approved construction are provided for the several pairs of change cylinders, the inking mech-

anisms applying the ink to the design cylinders 6 when offset printing and to the form cylinders 6* when relief printing.

The driving mechanism for the several movable parts of the press is as follows:

A cross shaft 9 is adapted to drive the common cylinder 5 in either direction, through a train of gears 10, 11, 12, 13. The common cylinder gear 13 is adapted to drive each pair of change cylinders through the gears 14, 15. The inking mechanisms are driven from the bevel gear 16 on the cross shaft 9 through the bevel gears 17 on the longitudinally disposed shafts 18, which shafts have bevel gears 19 meshing with bevel gears 20 on upright shafts 21, which upright shafts have bevel gears 22 meshing with bevel gears 23 on cross shafts 24. These cross shafts 24 carry gears 25 which drive the gears 26, which gears 26, in turn, drive the gears 27 and 28 on the shafts 27* and 28* respectively of the inking mechanisms.

The positively driven web roll, which is used when relief printing, is denoted by 29 and its coacting pressure roller by 30. The web roll 29 is driven from the common cylinder gear 13 through the gears 31, 32, 33.

It is intended that the printing press be driven in one direction for offset printing and in the reverse direction for relief printing.

When the press is to be used for offset printing, the pairs of design and transfer cylinders are placed in their proper positions in the press frame. The web 1 is led from the web supply 2 over suitable direction rollers 34 to the top of the common cylinder 5 and around the same in one direction, the cylinder 5 in this instance acting as a common impression cylinder for the several transfer cylinders 7. The printing web is then led away from the top of the common cylinder 5, over direction rollers 35 to the web rewinding roll 3.

When the press is to be used for relief printing, the pairs of design and transfer cylinders are replaced by the pairs of form and impression cylinders 6*, 7*. The web 1 is led from the web supply roll 2 over the direction rollers 34 to the top of the common cylinder 5 and around the same in the reverse direction, the cylinder 5 in this instance acting as a rotary carrier for the web, to steady the same and insure proper color register. The web is then led from the cylinder 5 between the form and impression cylinders of the several pairs of change cylinders and from thence between the positively driven web roll 29 and its pressure roller 30. The web is then led 55

over the direction rollers 35 to the web rewinding roll 3.

It will thus be seen that the press may be utilized either for offset or relief printing in colors upon a running web, with a slight amount of change in the press, thus effecting a material saving in cost without sacrificing efficiency and accurate color registry.

It is evident that various changes may be resorted to in the construction, form and arrangement of the several parts without departing from the spirit and scope of my invention, and hence I do not intend to be limited to the particular embodiments herein shown and described, but

15. What I claim is:

1. In a convertible web printing press for optional offset or relief printing, a common cylinder and a plurality of pairs of change cylinders arranged around the common cylinder, the common cylinder acting as an impression cylinder when offset printing and as a rotary web carrier when relief printing, and the change cylinders of each pair adapted to serve as design and transfer cylinders when offset printing and as form and impression cylinders when relief printing, and inking mechanisms for said design or form cylinders and means for leading the web around the common cylinder when offset or relief printing and also between the form and impression cylinders when relief printing.

2. In a convertible web printing press for optional offset or relief printing, a common cylinder, a plurality of pairs of change cylinders arranged around the common cylinder, the common cylinder acting as an impression cylinder when offset printing and as a rotary web carrier when relief printing, the change cylinders of each pair adapted to serve as design and transfer cylinders when offset printing and as form and impression cylinders when relief printing, and means for leading the web around the common cylinder when offset or relief printing and also between the form and impression cylinders when relief printing.

45. 3. In a convertible web printing press for optional offset or relief printing, a common cylinder acting as an impression cylinder when offset printing and as a rotary web carrier when relief printing, a plurality of pairs of change cylinders arranged around the common cylinder, the change cylinders of each pair adapted to serve as design and transfer cylinders when offset printing and as form and impression cylinders when relief printing, means for driving the press

in one direction for offset printing and in the reverse direction for relief printing without changing the direction of travel of the web to and from the press, and means for leading the web around the common cylinder when offset 5 or relief printing and also between the form and impression cylinders when relief printing.

4. In a convertible web printing press for optional offset or relief printing, a common cylinder acting as an impression cylinder when offset 10 printing and as a rotary web carrier when relief printing, a plurality of pairs of change cylinders arranged around the common cylinder, the change cylinders of each pair adapted to serve as design and transfer cylinders when offset print- 15 ing and as form and impression cylinders when relief printing, a positively driven web roll, and means for leading the web around the common cylinder when offset or relief printing, and also between the form and impression cylinders and 20 over the positively driven web roll when relief printing.

5. In a convertible web printing press for optional offset or relief printing, a common cylinder, a plurality of pairs of change cylinders ar- 25 ranged around the common cylinder, means for leading the web to and around the common cylinder in one direction for offset printing and to and around the common cylinder in the reverse direction for relief printing and also between the 30 change cylinders of each pair for relief printing, and means for driving the press in one direction for offset printing and in the reverse direction for relief printing.

6. In a convertible web printing press for optional offset or relief printing, a common cylinder acting as an impression cylinder when offset 35 printing and as a rotary web carrier when relief printing, a plurality of pairs of change cylinders arranged around the common cylinder, the change cylinders of each pair adapted to serve as design and transfer cylinders when offset printing and as form and impression cylinders when relief printing, means for leading the web to and around the common cylinder in 45 one direction when offset printing and to and around the common cylinder in the opposite direction when offset printing, and also between the form and impression cylinders of each pair when relief printing, and means for driving the press in one direction for offset printing and in the reverse direction for relief printing.

HOWARD M. BARBER.
